(57) **CLAIM**

The ornamental design for a cup holder, as shown and described.

DESCRIPTION

FIG. 1 is a first perspective view of a cup holder according to the present invention;

FIG. 2 is a second perspective view of the cup holder of FIG. 1;

FIG. 3 is a front view of the cup holder of FIG. 1;

FIG. 4 is a rear view of the cup holder of FIG. 1;

FIG. 5 is a first side view of the cup holder of FIG. 1;

FIG. 6 is a second side view of the cup holder of FIG. 1;

FIG. 7 is a top view of the cup holder of FIG. 1; and,

FIG. 8 is a bottom view of the cup holder of FIG. 1.

The broken line showing of a cross-shaped element in FIG. 7-8, ribbing, rings and flat surfaces in FIG. 8, a ring with 4 extensions in FIG. 7 and rear section in FIGS. 1-8 are included for the purpose of illustrating portions of the article that form no part of the claimed design.

1 Claim, 5 Drawing Sheets

FIG. 1

FIG. 2

FIG. 3

FIG. 4

FIG. 5

FIG. 6
